UNITED STATES PATENT OFFICE.

HOSFORD D. KELLOGG, OF HAVERFORD, PENNSYLVANIA.

RADIATOR.

1,371,031.

Specification of Letters Patent.

Patented Mar. 8, 1921.

Application filed November 20, 1918. Serial No. 263,317.

To all whom it may concern:

Be it known that I, HOSFORD D. KELLOGG, a citizen of the United States, residing at Haverford, in the county of Delaware and State of Pennsylvania, have invented certain new and useful Improvements in Radiators, of which the following is a specification.

The object of this invention is to provide a radiator comprising a plurality of independent sections, each section being so formed as to embody a vertically extending front chamber, rearwardly projecting tapering extensions of said chamber, and tubular sections connecting said extensions.

Another object is to provide such a radiator in which said tubular sections progressively decrease in cross-section rearwardly, and of such shape in cross-section as to radiate all heat laterally from their common plane.

A further object is to provide a radiator unit, comprising a vertically extending front chamber having a substantially flat outer face and rearwardly converging sides, oppositely directed lateral openings adjacent to said face for nipple connections, rearwardly projecting tapering extensions of said chamber, and vertically extending tubular sections connecting said extensions and progressively decreasing in their cross-sections from said chamber rearwardly.

A still further object is to provide a radiator formed of end and intermediate sections having front surfaces, lying substantially in a plane, and adapted to be united by means of nipple connections adjacent to their said front surfaces, the forward portions of the end sections projecting laterally and provided with openings in the rear walls of said 40 projections for valve connections, and said projections being adapted to shelter and substantially hide from view valves connected directly thereto.

And still another object is to provide a perforated grid for such radiators, and offsets upon adjacent walls of neighboring radiator sections, together with resilient means carried by said grid and operative to yieldingly lock said grid to said sections by interengagement of said means with said offsets.

Numerous other objects and advantages of the device, as well as various novel details in the construction thereof, are fully brought out in the following specification, when read

in conjunction with the accompanying drawings, in which Figure 1 is a front elevation of one of the preferred embodiments of the invention; Fig. 2 is a rear elevation of the same; Fig. 3 is an enlarged top plan view of the same showing the improved gratings or grids in operative position; Fig. 4 is a detailed sectional view of a portion of the radiator shown in Fig. 3 and illustrating the method of securing said grids in position; Fig. 5 is a vertical transverse section of one unitary radiator member taken on the line 5—5 of Fig. 3; Fig. 6 is a similar section of the radiator taken on the line 6—6 of Fig. 3; Fig. 7 is a horizontal section taken on the line 7—7 of Fig. 6; and Fig. 8 is a similar section of one type of radiator end unit.

Referring to the drawings, the preferred embodiment of this invention is shown as comprising a radiator which may be of a height similar, or equal, to that of the surface, wainscoting, or other part of the architectural finish of the interior of a room, said radiator as a unit being made up of a plurality of end and intermediate sections, which may be of any number and height for the purpose of providing substantially any desired amount of heat-radiating surfaces.

The end sections 1 and 2 are provided respectively with inlet and outlet ports for the heating fluid employed, the flow of the latter being regulated by means of valves 3 and 4 attached to said ports at the lower and uppermost portions of said end sections. In fact, each of said end sections is provided with two such ports, but when one of those in a given section is employed, the other may be closed by means of a suitable plug 5 or by the other valve. These sections comprise a longitudinally extending fluid channel 6, having a front wall surface 7, terminating in one direction in an outer wall surface 8, disposed perpendicular to the said first surface and both of said surfaces being adapted to embody any desired external appearance for the purpose of making the radiator consistent in appearance with other architectural features of a given chamber or room of a building.

The fluid channel 6 is provided with a rearwardly projecting tapering section 9 which extends vertically for substantially the entire length of the section of which it forms a part, or may be positioned only at

the upper, lower and intermediate portions of the said section, thus forming fluid spaces 10, 11 and 12, connected to one another by means of tubular channels 13, which latter, as they progress rearwardly of said radiator sections, preferably decrease in cross-section and are respectively of such shape as to direct all radiant heat therefrom laterally from their common plane.

10 Between the two end sections, as shown in Figs. 1 to 3 inclusive, there may be positioned any desired number of intermediate sections which have frontal surfaces 14 which may be provided with any desired configurations to correspond with the external appearance of the surfaces 7 of the said end sections. To the rear of said frontal surfaces, each of said intermediate sections comprises vertically extending fluid channels having a substantially bell-shaped fluid channel 15, the upper and lower of said sections being connected together and to the said end sections by means of any suitable form of inclosed nipples 16 and hex-nipples 16'.

Each of the rearwardly extending portions of said radiator sections is provided with vertically extending integral projections 17, adapted to coöperate directly with the interior wall surface of a chamber or room in which the radiator is located, whether said projections are of the same extent vertically as the radiator units or not. Furthermore, each of the end and intermediate sections is provided at its uppermost portion with a flat-topped ridge 18, between which are located independently positioned grids 19, comprising longitudinal plates 20, connected by transversely extending integral bars 21, between which are formed apertures to permit the air heated by said radiator units to pass upwardly through said grids. Each grid is provided with a plurality of integral downwardly extending resilient fingers 22, adapted to yieldingly engage the sides of recessed or integrally projecting offsets 23 from the adjacent surfaces of neighboring radiator sections.

It is to be noted that in this type of radiator, the heating fluid flows through the inlet valve 4, or inlet 5, and into the adjacent end section, whence it flows through the longitudinal channels formed by the upper and lower portions of the wedge-shaped sections and the nipples 16 toward the other end section of the radiator, and thence out by means of the exit valve 3, while a portion of said heating fluid flows from said longitudinal channel through the various rearwardly tapering channels, connected together as before described, and out and through said last-named valve.

An assembled radiator thus comprises a plurality of longitudinally extending fluid channels and transversely upwardly extend-

ing channels, preferably adjacent to the frontal wall surface of the radiator, said last-named channels preferably decreasing from front to rear and at their rearmost portions being adapted to coöperate directly with the surface of a room or chamber, or with a lining thereof, in order to form upwardly extending air-flues bounded by said wall surface, said rearwardly and upwardly extending fluid channels and the frontal portion of said radiator units.

With such a construction, it is obvious that the radiant heat from a great portion of the exterior surface of said radiator units impinges directly upon the said chamber wall, thus raising the temperature of the latter and thereby the currents of air which pass immediately adjacent to it, in addition to heating said air-currents by means of convection from the heated radiator surfaces. Such a radiator as that described may be supported by any desired number of removable feet 24, which are preferably in alinement with the rearwardly extending portions of the radiator units and form therewith extensions of the latter as between neighboring air-flues, while the entire space below the radiator as a whole may be partially inclosed by any suitable form of artistic paneling such, for instance, as the solid panels and grids 25 and 26, shown in Figs. 1 and 2 as being respectively beneath the end and intermediate sections of the radiator.

With the type of radiator just described, it is also obvious that there is an added feature residing in the fact that the inlet and outlet ports from the end sections are directed rearwardly so that the valves secured therein are totally hidden to the rear of the fluid channels 6. On the other hand, if desired, a simpler form of end section may be provided, such for instance as that shown in detail in Fig. 8, wherein the frontal portion 27 of the vertically extending fluid channel preferably is of no greater extent laterally than the corresponding portion 15 of the intermediate section illustrated by Fig. 7. However, one side 28 of this element, instead of being provided only with spaced bosses, as also shown in Fig. 7, for the provision of nipple-engaging threaded portions 29, said side is provided with threaded openings 30 for the reception of suitable inlet and outlet valves, but the remaining portions of this side are equally as prominent as those parts immediately adjacent to said openings, and as a result may be provided with any desired ornamental configuration.

Herein there has been thus described a radiator formed of end and intermediate sections, the latter being cast independently of each other and of said end sections, so that each intermediate section comprises a vertically extending front chamber, having

a substantially flat outer face susceptible of innumerable modifications for the purpose of providing different designs and rearwardly converging sides, oppositely directed 5 lateral openings adjacent to said face for nipple connections, rearwardly projecting tapering extensions of said chamber, and vertically extending tubular sections connecting said extensions and progressively 10 decreasing in their cross-section from said chamber rearwardly.

Having thus described my invention, what I claim and desire to protect by Letters Patent of the United States is:—

15 1. A radiator unit, comprising a substantially vertical chamber, laterally projecting extensions from and of less transverse extent than said chamber, and tubular sections connecting said extensions.

20 2. A radiator unit, comprising a substantially vertical chamber, hollow laterally projecting and transversely tapering extensions of said chamber, and vertically extending tubular sections connecting said extensions 25 and progressively decreasing in their cross-sections from said chamber outwardly.

3. A radiator unit, comprising a vertically extending front chamber, rearwardly projecting and transversely tapering extensions 30 of said chamber, and tubular sections connecting said extensions.

4. A radiator unit, comprising a vertically extending front chamber having a substantially flat outer face and rearwardly converging sides, rearwardly projecting tapering extensions of said chamber, and vertically extending tubular sections connecting said extensions and progressively decreasing in their cross-sections from said chamber 40 rearwardly.

5. A radiator, comprising a section formed of superimposed rearwardly tapering portions, connected by vertically extending tubular portions respectively decreasing in 45 cross-section rearwardly.

6. A radiator, comprising an end section having a longitudinally extending offset, and means to secure a valve to said section projecting rearwardly from and concealed 50 behind said offset.

7. A radiator, comprising fluid channel sections, in combination with a perforated grid adapted to span the space between neighboring sections, and interengaging 55 means carried by said sections and said grid to yieldingly secure said grid in normal position, said means comprising integral lugs

on said sections and resilient lug-engaging fingers carried by said grid.

8. A radiator section, comprising a relatively elongated vertically extending chamber, a plurality of horizontally tapering rearward extensions from one end portion of said chamber, tubular sections connecting said extensions and progressively decreasing 65 in their cross-sections from said chamber outwardly, and means to secure to the rear wall of said chamber a valve, adjacent to said tapering extensions and protected by the opposite end portion of said chamber. 70

9. A radiator formed of intermediate sections, and end sections having longitudinally extending offsets, and means to secure a valve to said section projecting rearwardly 75 from and concealed behind said offset.

10. A radiator, comprising end and intermediate sections, interior nipples connecting said sections, said end sections embodying offsets to the rear walls of which are adapted to be connected valves, or pipe connections, and said end sections being provided with openings in alignment with and adapted to permit access to said nipples. 80

11. A radiator unit, comprising a vertically extending front chamber, rearwardly 85 projecting tapering extensions of said chamber, and vertically extending tubular sections connecting said extensions and progressively decreasing in their cross-sections from said chamber rearwardly and having 90 longer major axes lying in their common plane than their minor axes at an angle therewith.

12. A radiator unit, comprising a vertically extending front chamber having a substantially flat outer face and rearwardly converging sides, rearwardly projecting tapering extensions of said chamber, and vertically extending tubular sections connecting said extensions and progressively decreasing in their cross-sections from said chamber rearwardly, adjacent sections positively cooperating at a plurality of points and the space between said sections intermediate of said points being substantially 100 closed to screen the rear of said sections from the front. 105

In testimony whereof I have affixed my signature in presence of two witnesses.
